UNITED STATES PATENT OFFICE

HENRY LOUDENSLAGER AND WALTER J. LOUDENSLAGER, OF COLUMBUS, OHIO

MOLDING APPARATUS FOR SASH WEIGHTS

Application filed May 15, 1928. Serial No. 277,847.

This invention relates to the manufacture of sash weights and has for its object to provide improved molding apparatus by means of which sash weights of improved construction can be produced in large quantities rapidly and economically and at the same time to permit of the formation of finished sash weights of improved structural design.

It is another object of the invention to provide improved molding apparatus permitting of the molding of sash weights in solid cylindrical units and while said units are maintained at vertical positions. It has been customary to mold sash weights in halves, that is to say, one-half of the weight being formed in the drag section of the mold and the other half in the cope section, the drag and cope sections being assembled at the time of forming to produce the finished weight. The ordinary method of producing sash weights is, however, open to objection in that there is some difficulty in properly registering the mold pockets or cavities of both the drag and cope sections, with the result that imperfect products are often produced. In accordance with the present invention this objection is primarily removed by forming practically all of the sash weight in pockets or cavities formed in the drag section, the cope section being largely used for the purpose of providing gates or runners to permit of the filling of the pockets in the drag section with the metal.

A further object of the invention resides in means for providing an improved eye construction on the sash weights by providing a smoothly finished construction and one which is devoid of sharp corners or projections which tend to cut or destroy a cable connected with the eye.

For a further understanding of the invention reference is to be had to the following description and the accompanying drawings wherein:

Figure 1 represents a vertical longitudinal sectional view taken through the improved sash weight molding apparatus comprising the present invention,

Figure 2 is a horizontal sectional view taken

through the apparatus on the plane indicated on the line 2—2 of Figure 1,

Figure 3 is a detailed vertical sectional view taken through the drag section of the mold showing the latter in its initial position on the pattern base of the mold,

Figure 4 is a view in vertical transverse section showing the drag section inverted with the cope section arranged thereon and positioned for pouring,

Figure 5 is a detailed view in side elevation of the mold showing the drag and cope sections,

Figure 6 is a plan view of the cope section,

Figure 7 is an enlarged vertical sectional view taken through one of the patterns carried by the pattern base,

Figure 8 is a transverse cross sectional view on the line 8—8 of Figure 7,

Figure 9 is a similar view on the line 9—9 of Figure 7,

Figure 10 is a view in side elevation of a sash weight formed in accordance with the present invention,

Figure 11 is a bottom plan view thereof,

Figure 12 is a detail view showing a pair of drag sections and the method of packing molding sand therein.

Referring more particularly to the drawings, the numeral 1 designates the improved molding apparatus comprising the present invention in its entirety. This apparatus is formed to include a pattern base indicated generally by the letter B. The pattern base comprises a board or plate 2 arranged horizontally upon a supporting table 3. The plate 2 is provided at longitudinally and transversely spaced intervals with a plurality of pockets 4, the bottom of which being provided with axial and reduced openings 5 which, in turn, terminate in relatively enlarged sockets 6 which open to the bottom of the plate 2 and in vertical registration with the pockets 4.

Adapted to be positioned securely within the pockets 4 are vertical upstanding sash weight patterns 7. These patterns are of cylindrical form and each thereof is formed

to comprise a hollow cylindrical body 8, the lower portion of which being received within one of the pockets 4. Within the open lower end of each of the patterns there is located a split ripping sleeve 9 provided centrally with a tapering bore and adapted to be positioned within this bore is a conical plug or wedge 10. This plug or wedge is provided with a threaded axial opening adapted for the reception of a screw bolt 11, the shank of the latter passing through one of the openings 5 and has its headed end 12 arranged in one of the sockets 6. The bolt 11 further, is provided with a longitudinally extending bore 13 for a reason 10 to be hereinafter set forth. Similarly, the sockets 6 are connected with channels 14 which lead to the atmosphere and permit of a circulation of air freely into the interior of the cylindrical body 8. Obviously, by tightening the bolts 11, the wedge plugs 10 may be drawn tightly into the split sleeves 9, so as to expand the latter and to thereby frictionally hold the vertical pattern 7 in secured relationship with the pattern base board 2.

25 Further, each pattern is formed to include a head 15, which comprises a solid metallic body having a reduced lower portion 16 which is welded or otherwise positively secured to the upper end of one of the cylindrical bodies 30 8. Each head includes a pair of spaced upwardly extending pins 17 which receive thereon the tubular extensions 18 of a sheet metal eye section 19, the latter being formed, as will be later explained, to constitute a part of the 35 finished sash weight.

Adapted to be positioned upon and secured to the edge portions of the plate 2 is a gauge frame 20. This frame may be made in different heights for the purpose of controlling the size or weight of the finished sash weight produced by the apparatus. That is to say, the pattern bodies 7 are of fixed length, but by changing the height or thickness of the gauge frame 20, it follows that the length 40 of the finished sash weight may be regulated at will so that the various sizes of sash weights, now commonly manufactured, may be produced from the single set of patterns 7, this being effected by the mere change in 45 the rectangular gauge frame, which may be made in three or four different heights.

50 Adapted to rest on the upper edge of the gauge frame is a main stripper plate 21, and loosely carried upon this stripper plate is a false stripper plate 22, the plates 21 and 22 being provided with openings adapted for the reception of the vertically arranged patterns 7. The stripper plate 22 has its normal upper surface provided with ribs 23, which 55 produce runner openings or grooves in the sand body 24 of the drag section 25 of the mold, which runner grooves lead to the various pockets produced in the sand body 24 by the normal upper ends of the pattern 7, as shown in Figure 3.

The drag section comprises a flask frame 26 which is provided exteriorly with angle brackets 27. These brackets have their lower legs provided with openings provided for the reception of studs 28 which project upwardly from the ends of the false stripper plate 22, the said brackets and studs serving to properly position the frame 26 on the plate 22 and to prevent lateral shifting thereof when the sand body 24 is being packed into the frame 26 around the upper ends of the pattern 7. This packing of the sand body should be carried out quite carefully and best results have been obtained by placing an additional drag section on the top of the section 25, as indicated by dotted lines in Figure 12. A large quantity of green molding sand is then placed in the combined drag sections and a vibrator or bumper 29 is operated so as to jar or jolt the molding apparatus to cause the settling of the sand in the drag sections and thereby produce complete settling of the sand in compact quarter around the pattern 7. When this operation has been fully completed the extra drag section is removed and the sand leveled off even with the top of the drag section. A follower plate 29' is then placed on the top of the drag section, as shown in Figure 3, and this follower plate is clamped to the drag section and also to the stripper plate 22 by means of frictional clamps 30.

The bumper or vibrator consists of a piston 31 which is mounted for limited reciprocation within a casing 32 connected with the table 3. Compressed air obtained from a pipe line 33 is lead into the bottom of the casing, so as to cause the elevation of the piston 31 until the latter contacts with the under surface of the table 3. At this time an outlet port 34 is uncovered by the position of the piston, which reduces the air pressure in the casing and allows the piston to fall by gravity. The closing of the outlet port 34 then permits the air pressure to be built up in the casing to again effect the rising of the piston 31, this action is repeated as long as the vibrator or bumper is in operation.

To remove the drag section from the pattern 7 the invention contemplates the provision of a pair of air cylinders 35 located at opposite ends of the mold. These cylinders include reciprocating pistons 36, the stems of which project from the tops of the cylinders 35 and are provided with heads 37, compressed air obtained from the pipe line 33 is admitted by means of valves 38 into the bottom of the cylinders 35 so as to act on the pistons therein. This permits the pistons to rise carrying with them the heads 37. These heads then contact with lateral extensions 39 provided at the ends of the main stripper plate 21, continued upward movement of the piston 36 results in the elevation 120

of the main stripper plate and the mechanism supported thereon to substantially the dotted line position shown in Figure 1, in which position the patterns are substantially removed from the pockets 40 provided thereby in the sand of the drag section 25. It will be observed that when upward movement of the drag section is initiated, the studs or pins 17 provided on the upper end of the patterns 7 are removed from the eye section 19, and the latter are retained in the upper ends of the pockets 40. It has been found by providing the bores 13 in the bolts 11 and also the similar bores in the heads 15 that any tendency on the part of the eye sections to follow the patterns is eliminated. Were these ports or bores omitted there would be a tendency of the eye sections to cling to the upper ends of the patterns, due possibly to a partial vacuum produced in the eye sections when the pins or studs 17 are being removed from the extensions 18. The ports or bores effectively prevent the formation of such a suction or partial vacuum and therefore allow ready separation between the eye sections and the patterns.

After the drag section has been elevated by the action of the air cylinders to substantially the dotted line position shown in Figure 1 a yoke or other form of support (not shown) is attached to the longitudinally aligned bearing studs 41 which project from the ends of the flask frame 26. The drag section is then lifted free of the patterns 7 and the supporting base previously described which includes in secure relationship the false stripper plate 22, the frame 26 and the follower plate 29. The drag section is then reversed in position from that formerly described so that the eye sections will be situated in the bottoms of the pockets 40, as indicated clearly in the Figure 4. At this time the false stripper plate 22 is removed from the drag section and there is applied to said drag section the frame 42 of the cope. This cope has been previously filled and compacted with a body of sand as at 43, and the lower surfaces of this sand has been formed, as shown in Figure 6, to produce runner grooves 44, which register with the grooves produced in the sand of the drag section by the ribs 23, and which grooves lead to the pockets 40. Formed in the sand body 43 and in registration with the pockets 40 are numeral indentations 45 so that the size or weight of the finished sash weight will be molded in the lower end of each weight, as shown in Figure 11. The grooves 44 lead to a riser or gate 46 by means of which the molten metal may be poured into the cope section and thence by following the grooves or runners 44 into each of the pockets 40 of the drag section. It will be seen that the molten metal readily enters the hollow interior of the eye sections 19, so that the eye sections become in effect a

unitary part of the finished sash weight. The eye sections, as previously stated, are made of sheet metal and as a result the eye portion of each of the finished sash weights presents a smooth polished unbroken surface, which readily adapts itself to a cable or other flexible element connected therewith when the sash weight is in use. The round or smooth surface of the eye section specifically prevent the cutting of the cable or causing excessive wear thereof. Since the molten metal flows around the curved interior of the eye section it is impossible to separate the latter from the body of the sash weight.

In view of the foregoing it will be seen that the present invention provides for an apparatus of particular design for producing sash weights economically, rapidly and in a finished generally acceptable form. As a matter of fact, the finished sash weight is considerably generally superior in most respects to the ordinary sash weight heretofore generally used, in that the sash weight produced in accordance with the present invention provides a smooth perfectly rounded and cylindrical body portion which is cast mainly in but one section of the mold and further, is provided with the unitarily united eye section which is of smooth regular form devoid of sharp projections, angles or corners. Again, the apparatus permits the size, number or weight of the completed sash weight to be formed on the end of such sash weights, so that when the latter are stored in piles the grade or number of the sash weight may be readily determined from end view inspection, which is a decided advantage over the original method of placing the number or grade mark on the side of the weight or in the eye portion thereof.

While there has been described what is considered to be the preferred method of construction and of operation in carrying out the invention, nevertheless it will be understood that various changes and departures may be made from time to time without departing from the spirit or scope of the invention as the latter has been defined in the following claims.

What is claimed is:

1. In molding apparatus for producing sash weights, a base, a plurality of patterns adapted to be rigidly carried by and to extend vertically from said base, each of said patterns being formed to include a cylindrical body portion, the lower end of said body portion being formed to be received within a pocket provided in said base, frictional clamping devices situated in the lower end of said body portion, screws carried by said base and cooperative with said clamping devices, each of said screws being provided with an axial bore establishing communication between the interior of said body portion and the atmosphere, a head secured in the upper

portion of said body, the upper end of said head being provided with a pair of spaced pins, and a sheet metal eye section removably positioned upon such pins, said head being provided with a longitudinally extending bore establishing communication between the interior of said body portion and the interior of said eye section.

- 5 2. A molding apparatus for producing sash weights, a base, a plurality of patterns adapted to be rigidly carried by and to extend vertically from said base, each of said patterns being formed to include a cylindrical body portion, the lower end of said body portion being formed to be received within a pocket provided in said base, a head secured in the upper portion of said body, the upper end of said head being provided with a pair of spaced pins, a sheet metal eye removably positioned upon said pins, means for securing each of said patterns to said base and means for maintaining communication between the interior of said sheet metal eye and the exterior of said base.
- 10 25 3. A molding apparatus for producing sash weights, comprising a base, a plurality of spaced upright sash weight patterns arising from and rigidly secured to said base, a cope section positioned upon said base, said 30 cope section being adapted to contain a sand body for the reception of the upper portions of said patterns, means for raising and lowering said cope section relatively to said base and means provided in said patterns to prevent a vacuum above said patterns when said 35 cope section is raised.
4. A molding apparatus for producing sash weights, comprising a base, a plurality of spaced upright sash weight patterns arising from and rigidly secured to said base, a cope section, said cope section being adapted to contain a sand body for the reception of said patterns, and means provided in said patterns to prevent a vacuum above said patterns when said patterns and said cope section are dissociated.

In testimony whereof we affix our signatures.

HENRY LOUDENSLAGER.

50 WALTER J. LOUDENSLAGER.
